CLAIM

The ornamental design for a cutting tool handle, as shown and described.

DESCRIPTION

FIG. 1 is a perspective view of a cutting tool handle showing my new design, wherein the drawings have a photographic appearance;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view of the cutting tool handle, wherein the drawings have a CAD appearance;

FIG. 9 is front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is another perspective view thereof showing a using condition with a cutting tool.

The broken lines depict portions of the cutting tool handle in which the design is embodied that are not considered part of the claimed design.

1 Claim, 15 Drawing Sheets(56)
